HAND LUGGAGE CONSTRUCTION

Julius Ritter, Jr., Racine, Wis., assignor to Hartmann Trunk Company, Racine, Wis., a corporation of Wisconsin

Application October 22, 1942, Serial No. 462,969

3 Claims. (Cl. 190—41)

This invention relates to improvements in hand luggage construction.

A primary object of the present invention is to provide a hand luggage case which is entirely devoid of metal in its construction, including the frame members, fixtures, fittings, latches and handle mountings.

A further object of the invention is to provide a hand luggage case which is substantially lighter in weight than a hand luggage case of equal size and proportions constructed according to standard practice.

A further object of the invention is to provide a hand luggage construction wherein certain wall portions of the frame members include wood veneer sheets having certain edge portions morticed into rounded wooden rails for strength, rigidity and lightness.

A further object of the invention is to provide a hand luggage frame construction wherein metallic reinforcing elements for the corners are eliminated, the frame corner portions being reinforced by a novel juxtaposition of wooden, fiber, and leather or the like members.

A further object of the invention is to provide a hand luggage case construction wherein the carrying handles are secured to the case sections so that the leather or other covering material is relieved of much of the pulling strain.

A further object of the invention is to provide a hand luggage case construction wherein a pair of complementary carrying handles have their base portions so mounted and secured as to bring the complementary handles very close together and upright, for ease and convenience in engaging and grasping the same.

A further object of the invention is to provide a hand luggage case construction wherein the carrying handles are mounted on shouldered portions of the case section frames with the base portions of the handles permitting the same to fold over onto the top of the luggage case.

A further object of the invention is to provide a hand luggage construction which results in a light, rigid, and durable case devoid of metal, which is unique and attractive in appearance, which is strong, and which is well adapted for the purposes described.

With the above and other objects in view the invention consists of the improved hand luggage construction, and its parts and combinations as set forth in the claims, and all equivalents thereof.

In the accompanying drawing in which the

same reference characters indicate the same parts in all of the views:

Fig. 1 is a side and end perspective view of a hand luggage case constructed according to the present invention;

Fig. 2 is an enlarged, transverse, vertical sectional view of the hand luggage case, taken on line 2—2 of Fig. 1;

Fig. 3 is an enlarged, fragmentary view of an end upper corner portion of the hand luggage case, with parts broken away and in section, showing details of construction; and

Fig. 4 is a fragmentary, detail, sectional view on a still larger scale of a portion of the luggage case structure shown in Fig. 2.

Referring now more particularly to the drawing, it will appear that the improved hand luggage case comprises a pair of complementary sections 8 and 9 whose open faces are adapted to be brought into meeting relationship when the case is closed. The luggage case is of the type having soft or non-rigid side walls. All outer surface portions of the case section walls are covered by conventional flexible covering material, which in the better class of luggage is leather, but which might also be Fabrikoid, composition, canvas, or the like. To accomplish the soft side wall feature it will be observed from Fig. 2 that the taut, tenacious, flexible covering material 10 is not reinforced on the side wall portions of the case sections, but the inner surfaces of the same are merely covered with lining material 11. The meeting edge portions of the bottom walls of the complementary sections 8 and 9 are hingedly connected together by hinge strips formed by overlapping extents of the covering material 10 sewed together and to wall reinforcements, as indicated at 12 in Fig. 2.

The construction of one of the complementary sections 8 of the hand luggage case will now be described in detail. This is the shallower of the two sections and it will be observed that it is of U-formation in longitudinal and transverse section and includes the soft or flexible side wall previously mentioned, top and bottom walls, and end walls (referring to the position of the case in its closed, transportable condition). The formation of the top wall is best shown in Fig. 4. On the inner surface the lining material 11 terminates adjacent the leather or the like covering 13 for a shoulder-forming longitudinal wood rod or rail 14. The covering 13 completely embraces said rail and also a flat, elongated fiber strip 15 applied to the top flat face of the rail and projecting laterally from the free side there-

of. The fiber strip, with the rail to which it is applied, forms a valance overlapping and sealing the complementary rail portion of the case section 9 when the case is closed. Both end portions of the embracing covering 13 are interposed between the lining and covering 10 of the top wall, but terminate short of the side wall. Interposed between the extended end portions of the covering 13 is a fiber strip 16 whose transverse dimension is considerably less than that of the wall and which is spaced somewhat from the rigid rail 14 for reasons of flexibility. All of the plies in said top wall may be held together by a suitable adhesive.

In cases of the flexible or soft-sided type it is the practice to use a pair of complementary carrying handles which, when grasped are brought into convenient juxtaposition. In the present invention the complementary handle arrangement is such that the handle members are mounted so as to be very close together in their upright positions. The complementary handle members are also mounted in a manner so that the covering material for the case sections, which is leather or the like, is relieved of much of the pulling strain. That is to say, in the present improvements the handles are connected with structural elements other than the covering material. The arrangement in this respect is best shown in Fig. 4. It will be noted that a complementary handle member 17 has its lower portions merged into flat tabs 18 which extend toward the side wall of the case section which carries the handle and at right angles to the plane of the handle 17. The top ply of the rail covering 13, where it is extended below the top wall covering 14, provides a shoulder 19 against which the flanged tab 18 seats with the horizontal curved extent of the tab 18 being interposed between the flat extent of the upper ply of the rail covering 13 and the section outer covering 10. The longitudinal line of stitching 20 which parallels the inner edge of the covering 10 for the top extends through all of the superimposed plies of material, including the outer covering 10, the flat handle tab 18, the two plies of the rail covering 13, the fiber strip 16, and the lining 11. It should also be noted that the lower portion of the rail 14 is embraced by a strip of cloth 21 which has a horizontal extent underlapping the inner end portion of the fiber strip 16, and this is also passed through by the line of stitching. At the junction of the lower upright portion of the handle 17 with the angularly directed tab 18 the stock is relatively thin or compressed, and this permits the handle 17 to be folded over relatively flatly onto the top surface of the case section. The base portion of the upright extent of the handle 17 is reinforced, and the plies of material are held together by a line of stitching 22.

It is desirable that the bottom wall of the case section 8 be reinforced and have a certain degree of rigidity. The inner longitudinal edge along the open side of the bottom is reinforced by a curved rail 23 underlying and parallel to the upper rail 14. The lower inner edge portion of the rail 23 is morticed as at 24 to receive the longitudinal edge portion of a wood veneer sheet 25 which terminates short of the outer corner portion of the bottom wall. Inner surface portions of the wood veneer sheet 25 have applied thereto opposite end portions of a leather sheathing sheet 26 which also embraces the lower rail 23. Interposed between portions of the sheet 26

and the rail 23 is a layer of fabric 27 having one end portion below an extent of the sheathing sheet 26. The curved upper portion of the rail 23 has an outermost covering 28 of leather or the like which is a continuation of the outer covering of the bottom wall of the complementary section 9 of the case. Said extended covering 28 cooperates with the previously mentioned hinge strip 12 in the provision of a strong and effective hinge connection for the complementary case sections. The various plies in the bottom wall described are held together by a suitable adhesive and also by a longitudinal line of stitching 29.

The end wall construction of the case section 3 is illustrated in Fig. 3. A vertical curved rail 30 (see Fig. 2) forms a rigid reinforcement for the inner edge of said end wall. At its ends the rail is in abutment with end portions of the rails 14 and 23 of the top and bottom walls respectively. Secured to the outer face of the rail, and projecting beyond the free edge thereof is a fiber strip 31. In the closed relationship of the luggage case sections the outer faces of the top and end wall rails of the case section 3 form shoulders against which outer edges of the walls of the complementary case section 9 seat with the lines of meeting being covered by the projecting end wall fiber strips 31, as well as the top wall fiber strip 15, all of which form valances.

Inwardly of the end wall rail 30 and slightly spaced therefrom is a vertical fiber strip 32 which is interposed between and held by adhesive to lateral extents 33 and 34 of leather or the like covering 35 for the rail 30 and valance strip 31. The covering 35 is a continuation of that covering similar parts on the top and bottom walls and is brought about the corners in a taut, slightly rounded condition, as best shown in Fig. 1. The plane of the fiber strip 32 is inwardly slightly from that of the valance strip 31, whereby a slight shoulder is formed. The outermost covering material 10 for the end wall terminates at this shoulder and overlaps the outer lateral extent 33 of the rail covering 35. A line of stitching 36 follows said shoulder and passes through all of the superimposed plies of material in said portion of the end wall. The end wall outwardly of the fiber strip 32 is not reinforced and is composed only of the outer covering material 10 and the inner lining 11. While only one end wall of the section 3 has been described it will be understood that the other end wall of said case section is identical thereto.

Generally speaking the top, bottom, side and end walls of the complementary case section 9 are constructed similarly to the construction of the corresponding walls of the case section 8 described in detail. The major difference resides in the fact the edges of the walls adjacent the open side of the case section 9 are adapted to lodge against the rails 14, 23 and 30 of the case section 8 and are covered by the valance strips 15 and 31. Hence, on the walls of the case section 9 strips similar to the valance strips 15 and 31 are not carried by the rails 37, 38 and 39. The case section 9 is, however, deeper than the case section 8. Hence, the veneer panel 25 for the bottom wall, interposed between the outer covering 10 and the lining 11, is somewhat wider than the panel 25 in the other bottom wall.

The same is true respecting the fiber strip 16, which interiorly reinforces the top wall of the case section 10. This strip 16 is considerably wider than the strip 16 in the corresponding wall

of the case section 8, as will appear from Fig. 2.

The handle member 17' which is complementary to the handle member 17, has its flat horizontally extended tab portions 18' secured between plies of material of the top wall of the section 9 exactly similarly to that described in connection with case section 8. The outer covering 10 is thereby relieved of much of the pulling strain and both handle members project upwardly in convenient adjacency. When necessary, the handle member 17' may be bent over against the top wall.

The complementary sections 8 and 9 of the improved luggage case are adapted to be releasably secured in closed relation by a pair of flexible hasp devices 40 mounted on the top walls of the case sections and formed of leather or the like. These non-metallic hasp devices will not be described as they form the subject-matter of my co-pending application filed on even date herewith.

In keeping with the elimination of metal from the case structure the interior of one of the sections may be equipped with suitable non-metallic fixtures (not shown) for the draping and folding of suits and garments.

The elimination of metal from the luggage case makes it a relatively light structure. Strength is in no wise sacrificed because of the novel wall structure. The appearance of the case is attractive, unique and rugged, and the construction is simple, novel, and well adapted for the purpose described.

What is claimed as the invention is:

1. In a hand luggage case, an enclosing wall formed with an outer covering of leather and an inner fabric lining, a rigid wooden rail extending along an outer longitudinal edge of said wall projecting perpendicularly of a face of said wall and having a rounded surface portion, a flexible sheathing embracing the rail and having end portions secured between the outer covering and

the lining, an inner portion of said rail being formed with a longitudinal rabbet, and a wooden reinforcing panel of less width than said wall interposed between the end portions of the sheathing and between portions of the covering and lining and having the longitudinal edge secured within said rail rabbet.

2. In a luggage case, a pair of complementary sections having adjacent top multi-ply walls in meeting relationship, the meeting edge portions of said walls including rigid rails, multi-ply wall portions connected to and extending away from said rails, each of said multi-ply wall portions including an outer flexible covering and an internal, stiff reenforcement, each of said reinforcements being offset from the exterior surface of each rail to form therewith an angular seat, a complementary handle member for each section extending perpendicularly from the section top wall and having an angular flexible base tab extending between plies of the top wall at the shoulder adjacent the rail and secured directly to said stiff reenforcement, the angle formed between said base and said handle being seated in said angular seat, and means for holding said reenforcement in its offset relation.

3. In a hand luggage case, an enclosing wall formed with an outer covering of leather and an inner fabric lining, a rigid wooden rail extending along an outer longitudinal edge of said wall, a fiber strip secured to the outer face of said rail and projecting beyond the free edge thereof, a relatively narrow fiber strip interposed between the covering and lining adjacent but spaced from the rail, and a flexible sheathing embracing the rail and having edge portions staggered and embracing portions of the fiber strip between the covering and lining, said fiber strip and sheathing terminating substantially short of the wall margin opposite the rail.
